CLAIM

The ornamental design for a household machine or appliance for aerating water as shown and described.

DESCRIPTION

1. Household machine or appliance for aerating water

1.1 : Front

1.2 : Perspective

1.3 : Perspective

1.4 : Right

1.5 : Front view with bottle shown aside the docking station for ease of illustration of the claim

1.6 : Perspective view with bottle shown aside the docking station for ease of illustration of the claim

1.7 : Perspective view with bottle shown aside the docking station for ease of illustration of the claim

1.8 : Top

Household machine or appliance for carbonating water (also for the non-stationary use “on-the-go”); reproductions 1.1-1.4 and 1.8 show the claimed design with all elements connected, whereas reproductions 1.5-1.7 show the claimed design with a bottle disconnected; minor variations in color are due to different lighting conditions; any shadows are for illustrative purposes only and form no part of the claimed design.

1 Claim, 8 Drawing Sheets
